SCRAPER AND POLISHER FOR INTERNAL COMBUSTION ENGINES

Samuel B. Smith, Rocky River, Ohio

Application August 7, 1934, Serial No. 738,840

27 Claims. (Cl. 123—198)

This invention relates to improvements in devices for scraping the carbon deposits forming on pistons and in the cylinders of internal combustion engines and the like.

5 The formation of carbon deposits, on the top of the piston and in the cylinder, causes a serious decrease in the operating efficiency of an internal combustion engine, due to the absorption of heat by the carbon covered surface. Obviously, therefore, the operating efficiency of an internal combustion engine could be appreciably increased, if means were provided for scraping the carbon deposits from the interior surfaces of a cylinder and the top of the piston, so that 15 a smooth, polished surface was provided which would reflect rather than absorb the heat.

In air cooled or other high temperature engines, the pistons frequently melt out on account of the high temperature from absorption of heat 20 which could be avoided if the heat were reflected instead of absorbed.

Therefore, an object of this invention is to provide new and novel means for scraping and polishing the interior walls of a cylinder and the top of a piston, in an internal combustion engine, and to actuate such scraping means by means 25 operating within the cylinder.

Another object is to provide means for scraping carbon deposits from the interior of a cylinder having a sleeve operating therein, and especially to scrape and polish the cylinder wall 30 between the top of the sleeve and the head of the cylinder.

Another object is to provide means, for scraping the carbon deposits from the interior of a cylinder, which are actuated by the action of a sleeve valve and therefore are positive and efficient in operation.

Another object is to provide a scraper with 40 sufficient surface in contact with the wall to transfer to the contacting metal the heat absorbed by the surface exposed to the gases, so that its temperature will not be high enough to cause pre-ignition or detonation.

Another object is to provide a piston scraper to which movement is imparted intermittently and in one direction only, the same taking place only during the lower half of the travel of the piston. Also, an object is to provide means for preventing the scraper from moving back during 45 the idling period.

Still another object is to provide a simple, durable and efficient piston scraper, which can be installed in conventional engine constructions 50 with a minimum amount of work and at a rela-

tively low cost, and to generally improve upon piston scrapers.

These and other objects will appear during the course of the following description.

In the drawing, forming a part of this application:

Fig. 1 is a broken vertical sectional view through the top of a cylinder showing my scraper means installed therein, the same being taken on the line 1—1 of Fig. 2;

Fig. 2 is a view similar to Fig. 1, taken on the line 2—2 of Fig. 1;

Fig. 3 is a fragmentary section taken on the line 3—3 of Fig. 1; while

Fig. 4 is a top plan view of the piston scraper 15 and sleeve.

In the drawing the numeral 10 indicates a cylinder of an internal combustion engine, having a rotating sleeve valve 10a, provided at its top with two integrally formed lugs 10b, which are adapted to scrape carbon deposits forming 20 on the inside cylinder wall between the top of the sleeve 10a and the cylinder head 9. A piston 11, reciprocating within the sleeve 10a, carries the usual piston rings 12, and is provided centrally with a depending portion 13, having a longitudinal bore 14 shouldered at 15, where adjusting shim 20 is fitted. A connecting-rod 16, mounted on a piston-pin 17, is adapted to be connected to, and actuated by a crank-shaft not 30 shown herein.

The means for scraping the top of the piston 11, for keeping it free of carbon deposits, comprise a piston-scraper 18, having two arms 19, adapted to scrape the top of the piston 11, which 35 are formed integrally with a central circular shank 21, fitted into the bore 14 of the depending portion 13 of the piston 11, and provided with a reduced end portion which is threaded externally at 22. Drilled oil holes 23 are provided 40 in the depending portion 13 of the piston 12 to permit oil to lubricate the shank 21 in the bore 14 of the piston 11. As shown in the drawing, the arms 19 of the piston-scraper 18 are flat on 45 their bottom surfaces which are in contact with the top of the piston 11, are curved on their upper surfaces, and taper away in thickness from the shank 21 to the ends thereof. For certain uses it may be advantageous to remove a portion of the contacting metal of the scraper arms 19, to 50 facilitate the scraping action, and such construction is within the scope of my invention.

It will be noted that the flat surface gives the greatest contact for the disposal of heat, thereby preventing detonation or pre-ignition from hot 55

spots within the cylinder. This construction also provides that the heat within the cylinder will be absorbed by the curved surface of the scraper, and the flat surface being in contact with the piston or cylinder wall, which has a lower temperature, on account of the heat being reflected by the piston, instead of being absorbed by it, will impart or transfer the heat to the piston, thus making the exposed surface of the scraper 10 hotter than the contact surface, causing it to warp or spring down at the end, as well as in the middle, thus making a good contact throughout the length of the scraper arms.

It will be noticed, that the piston scraper 18 has two arms 19 which balance and cause the pressure, from within the cylinder 10, to press down equally throughout their length, and therefore do not have to be held in position by the alignment of the bearing, or clearance of the bearing in which they rotate, but are kept in contact by the thrust bearing, which can be easily adjusted by changing the thickness of the shim 20.

The means for driving the piston-scraper 18 comprise an operating arm 24, secured to the connecting-rod 16 by means of a set-screw 25, provided with a spring 26, to keep the operating arm 24 properly spaced. A gear-sector 27, mounted on the top of the operating arm 24, 30 drives a cooperating gear-sector 28, mounted on a collar 29, screw threadedly mounted around the threaded portion 22 of the shank 21. It will be apparent, that the rocking movement imparted to the gear-sector 27, on the operating arm 24, by the rocking movement of the connecting-rod 16, might likewise impart a rocking movement to the cooperating gear-sector 28 secured to the collar 29, and thus might impart a continuous oscillating movement to the scraper arms 19, if special means were not provided to prevent this.

It has been found desirous to impart an intermittent rotating movement to the scraper arms 19, in order that they will be actuated only during the lower half of the travel of the piston 11, and will be inactive or idle during the upper half of the piston travel. The foregoing is accomplished by means of a double clutch, of which the collar 29 forms a part.

It will be noticed, that the top of the collar 29 rests against the shoulder 15 in the bore 14 of the depending portion 13 of the piston 11. This construction forms a center bearing means, and prevents the warping of the scraper arms 19 away from the top of the piston 11, which otherwise might occur, on account of the high temperatures to which the scraper arms 19 are subjected.

The lower clutch, as shown in section in Fig. 3, comprises cut-out portions 31 in the collar 29, having inner edge portions 32 receiving rollers 33 pressed away from the inner edges 32 by springs 34. When the connecting-rod 16, 60 through the operating arm 24 and gear-sector 27 mounted thereon, moves the cooperating gear-sector 28 on the collar 29 in a counter-clockwise direction, as viewed in Fig. 3, it draws the rollers 33 away from the inner edge portions 32 and wedges them between the inner surface of the gear-sector 28 and the small end of the cut-out portions 31 of the collar 29, causing the collar 29, secured to the shank 21, to be rotated in the bore 14 in the depending portion 13 of the piston 11. The rotation of the shank 21

moves the scraper arms 19 around on the top of the piston 11.

When, however, the gear-sector 28 is rotated in a clockwise direction by the rocking movement of the connecting-rod 16, the rollers 33 are drawn towards the inner edges 32, against the action of the springs 34 and do not engage the inner surface of the collar 29, and thus permit the gear-sector 28 to move around the collar 29 without driving it.

A second clutch mounted above the lower clutch is provided in order to prevent movement of the piston-scraper 18 during its idling period, and is indicated by the numeral 35, and is provided with rollers 36 bearing against the bore 14 in the depending portion 13 of the piston 11. This second clutch 35 is of a construction similar to the lower clutch, with the exception that it is not provided with a gear-sector. It operates in an obvious manner in the bore 14 to prevent the scraper 18 from moving back during its idling period.

The actuation of the piston scraper 18, as previously explained, occurs only during the lower half of the travel of the piston, in order that the high pressure and intense heat generated during the compression and ignition strokes may not interfere with the operations of the piston scraper 18.

The means for scraping carbon deposits from the inner surface of the cylinder-head 9, comprise a scraper 38, having two arms 39, formed integrally with a central circular shank 41, extending through a circular aperture 42 in the cylinder head 9, and provided with a nut 43 around its top end. The scraper arms 39 are of a construction similar to the arms 19 of the piston scraper 18, with the exception that they are slightly longer than the latter arms, as they extend to the cylinder wall 10. As shown in Fig. 2, rotation of the sleeve 10a will cause the sleeve lugs 10b to press against the scraper arms 39 and to thus rotate them around the circular shank 41, to scrape carbon deposits from the inner surface of the cylinder-head 9.

The lugs 10b, formed at the top of the sleeve 10a, operate to scrape the carbon deposits forming on the inside cylinder wall between the top of the sleeve 10a and the cylinder-head 9. It is contemplated that special scraping edges may be provided on the lugs 10b, although satisfactory results may be obtained without any special scraping edges. Such scraping means, as for example, removing a portion of the contacting metal of the lugs, are within the contemplated scope of my invention.

It, therefore, will be apparent to those skilled in the art that my invention may be variously changed, used or modified without departing from the spirit of my invention or sacrificing the advantages thereof, and that the embodiment of my invention herein disclosed is illustrative only, and that my invention is not limited thereto.

What is claimed is:

1. A piston scraper for an internal combustion engine, comprising a scraper for scraping the top of the piston, and means for actuating the scraper intermittently and in one direction only.

2. A piston scraper for an internal combustion engine, comprising a scraper for scraping the top of the piston, means for actuating the scraper intermittently and in one direction only, and means for preventing movement of the scraper during its idling period.

3. A piston scraper for an internal combustion

5 engine, comprising a scraper for scraping the top of the piston, a one-way clutch operatively connected to the scraper, means for transmitting the rocking movement of the connecting-rod to the clutch for driving the scraper intermittently and in one direction, and means for preventing movement of the scraper during its idling period.

10 4. A piston scraper for an internal combustion engine, comprising a scraper for scraping the top 10 of the piston, a one-way clutch operatively connected to the scraper, means for transmitting the rocking movement of the connecting-rod to the clutch for driving the scraper intermittently and in one direction, and a second one-way clutch operatively connected to the scraper for preventing movement of the scraper during its idling period.

15 5. A piston scraper for an internal combustion engine, comprising means for scraping the top of the piston, an operating arm connected to the connecting-rod, a gear-sector mounted on the arm, a one-way clutch operatively connected to the scraping means for intermittently moving the scraper means in one direction, and a gear-sector secured to the clutch and adapted to be driven 20 by the gear-sector on the operating arm.

25 6. A piston scraper for an internal combustion engine, comprising means for scraping the top of the piston, and means for actuating the scraping means by the movement of the connecting-rod, 30 said actuating means being operative to actuate the piston scraper only during the lower half of the travel of the piston.

35 7. A piston scraper for an internal combustion engine, comprising arms rotatably mounted around a central pivot on the top of the piston, and driving means operatively connected to the connecting-rod for rotating the arms by the rocking movement of the connecting-rod, said driving means being operative to drive the piston scraper 40 only during the lower half of the travel of the piston.

45 8. A piston scraper for an internal combustion engine, comprising means for scraping the top of the piston, means for actuating the scraping means by the movement of the connecting-rod, 50 said actuating means being operative to actuate the piston scraper only during the lower half of the travel of the piston, and means for preventing actuation of the piston scraper during the upper half of the travel of the piston.

55 9. A piston scraper for an internal combustion engine, comprising arms rotatably mounted around a central pivot on the top of the piston, driving means operatively connected to the connecting-rod for rotating the arms by the rocking movement of the connecting-rod, said driving means being operative to drive the piston scraper only during the lower half of the travel of the piston, and means for preventing movement of the piston driving means during the upper half of the travel of the piston.

60 10. In a device of the character described, a piston having a central depending portion provided with a longitudinal bore, a piston scraper 65 comprising arms adapted to scrape the top of the piston and terminating in a shank fitting into the bore in the depending portion, and means for rotating the shank of the scraper from the rocking movement of the connecting-rod for rotating the scraper arms on the top of the piston.

70 11. In a device of the character described, a piston having a central depending portion provided with a longitudinal bore, a piston scraper comprising arms adapted to scrape the top of the piston and terminating in a shank fitting

75 into the bore in the depending portion, and means for rotating the piston scraper from the rocking movement of the connecting-rod, said means being operative to rotate the scraper only during the lower portion of the travel of the piston.

12. A piston scraper, comprising arms having flat surfaces in contact with the piston and curved surfaces exposed to the gases, and means for actuating said arms.

10 13. A piston scraper, comprising arms having flat surfaces in contact with the piston and curved surfaces exposed to the gases, and means for actuating said arms during the lower half of the travel of the piston.

15 14. A piston scraper, comprising arms having flat surfaces in contact with the piston and curved surfaces exposed to the gases, means for actuating said arms only during the lower half of the travel of the piston, and means for preventing movement of the arms during the upper half of the travel of the piston.

20 15. A piston scraper for an internal combustion engine, comprising arms movable on the top of a piston, said arms having curved upper 25 surfaces whose radii in cross section are approximately one-half the width of the arms, and means for moving the arms on the piston.

25 16. A piston scraper for an internal combustion engine, comprising arms movable on the top of a piston, said arms having curved upper 30 surfaces whose radii are approximately one-half the width of the arms, and having flat surfaces in contact with the piston, and means for moving the arms on the piston.

35 17. A device for scraping a cylinder wall of an internal combustion engine, comprising arms movable on the inner top cylinder wall, said arms having curved upper surfaces whose radii are approximately one-half the width of the 40 arms, and means for actuating the arms on the wall.

45 18. A device for scraping a cylinder wall of an internal combustion engine, comprising arms movable on the inner top cylinder wall, said arms 45 having curved upper surfaces whose radii are approximately one-half the width of the arms, and having flat surfaces in contact with the piston, and means for moving the arms on the wall.

50 19. In a device of the character described, the combination of a cylinder, a rotating sleeve valve in the cylinder, and arms movable on the inner top cylinder wall and operatively connected with the sleeve to cause the rotation of the sleeve to move the arms on the wall.

55 20. In a device of the character described, the combination of a cylinder, a rotating sleeve valve in the cylinder, arms mounted on a rotatable shank in the cylinder wall, and connections between the sleeve and the arms to cause the rotation of the sleeve to move the arms on the wall and around on the shank.

60 21. In a device of the character described, the combination of a cylinder, a rotating sleeve valve in the cylinder, and arms movable on the inner top cylinder wall mounted on a rotatable shank in the sleeve wall and operatively connected with the sleeve to cause the rotation of the sleeve to rotate the arms on the cylinder wall.

65 22. In a device of the character described, the combination of a cylinder, a rotating sleeve valve in the cylinder, and arms movable on the inner top cylinder wall, said arms having curved outer surfaces whose radii are approximately one-half the width of the arms and being operatively con- 70

75

nected with the sleeve to cause the rotation of the sleeve to move the arms on the wall.

23. In a device of the character described, the combination of a cylinder, a rotating sleeve valve 5 in the cylinder, arms movable on the inner top cylinder wall, said arms having curved outer surfaces whose radii are approximately one-half the width of the arms, and flat surfaces in contact with the piston and being operatively connected 10 with the sleeve to cause the rotation of the sleeve to move the arms on the wall.

24. In combination, a cylinder, a rotatable sleeve in the cylinder, and means operated by the rotating sleeve for scraping carbon deposits 15 from the inside wall of the cylinder.

25. In combination, a cylinder, a rotatable sleeve in the cylinder, and lugs on the top of the sleeve bearing against the cylinder wall and

adapted to scrape carbon deposits from the cylinder wall upon rotation of the sleeve.

26. In combination, a cylinder, a rotatable sleeve in the cylinder, and lugs on the top of the sleeve extending to the cylinder head and 5 bearing against the cylinder wall, for scraping the carbon deposits from the cylinder wall between the top of the sleeve and the cylinder head whenever the sleeve is rotated therein.

27. A scraper for a surface of an internal combustion engine, consisting of a member having a surface in contact with the engine surface, a shaft extended from near the center of the contact surface at right angles to said contact surface, and a thrust bearing on the opposite end 10 of the shaft from the member holding said contact surfaces together.

SAMUEL B. SMITH.
